100.8

UNITED STATES PATENT OFFICE.

CLIFTON D. PETTIS, OF NEW YORK, N. Y.

BRAKE SHOE.

Application filed June 22, 1923. Serial No. 647,045.

To all whom it may concern:

Be it known that I, CLIFTON D. PETTIS, a citizen of the United States, residing at the city of New York, county and State of New York, have invented certain new and useful Improvements in Brake Shoes, of which I do declare the following to be a full, clear, and exact description, reference being had to the accompanying drawings, forming a 10 part of this specification.

The present invention relates more particularly to that class of brake shoes for railway cars, in which the body of the shoe is reinforced or strengthened at its back, and the object of the invention is to provide an improved construction of end lug, which co-operates with some suitable form of center lug, in holding the brake shoe in proper position upon the brake head.

20 The invention consists in the improvements hereinafter described, illustrated in the accompanying drawings and particularly pointed out in the claims at the end of this specification.

25 Figure 1 is a plan view of one end of a brake shoe embodying my invention. Figure 2 is a view in vertical section on line 2—2 of Fig. 1. Figure 3 is a plan view of a portion of the back of the shoe with the 30 end lug removed. Figure 4 is a view of the blank from which the end lug will be formed. Figure 5 is a plan view of the finished end lug. Figure 6 is a view in elevation of the end lug looking towards the end 35 of the shoe. Figure 7 is a view similar to Fig. 1 but showing a modified form of the invention. Figure 8 is a view similar to Fig. 2 but showing the back plate with a T-shaped transverse opening. Figure 9 is a 40 view in central vertical section through Fig. 7. Figure 10 is a view of the blank from which the modified end lug is formed. Figure 11 is a plan view of the modified end lug. Figure 12 is a view in elevation of the 45 end lug looking towards the end of the shoe.

I have not deemed it necessary in the accompanying drawings to illustrate an entire brake shoe, as my invention pertains to the end lug portion only of the shoe. In an application filed by me in the United States Patent Office September 2, 1922, Sr. No. 585,906, which has matured into Patent No. 1,470,478, October 9, 1923, there is shown a type of brake shoe for use in connection with which my invention is particularly well adapted.

The brake shoe is shown as comprising a cast metal body A and a pan-shaped reinforcing member B. Preferably the member B comprises a ductile metal back plate provided at its sides and ends (one end only being shown) with integral walls, preferably of expanded or reticulated metal, which serve to strengthen the body of the 60 shoe.

The in the form of the invention illustrated upon sheet 1 of the drawings, my improved end lug is preferably formed from a sheet metal blank of the shape shown in Fig. 4 of the drawings. The finished end lug comprises a channel or box-like body adapted to extend transversely of the shoe, this body having upon its side nearest the center of the shoe upstanding, inwardly projecting walls that serve to center the brake shoe 65 upon the brake head. To form the finished lug, the sheet metal blank of the shape shown in Fig. 4 of the drawings, is bent upon the lines 10 and 11 to form the top C and the front or outer and rear or inner 70 walls D and E of the lug; and the blank is bent upon the lines 12 and 13 to form the end walls F and G of the body (when end walls are used); is bent upon the line 14 to form the inwardly extending part H, and is 75 bent upon the lines 15 and 16 to form the upstanding centering walls I and J. When the blank is thus bent, the lug will assume the shape shown in Fig. 5 of the drawings. To enable the upstanding walls I and J to 80 be bent upwardly, slits 17 and 18 are formed 85 in the blank.

In order that the finished lug may be attached to the brake shoe, there are provided a number of flanges or tongues adapted to extend beneath and interlock with the reinforcing back plate of the shoe. To this end, the wall D is provided with a flange 90 d, the end walls F and G are provided respectively with flanges f and g, and the part H is provided with a flange h bent at right angles thereto.

In applying the improved end lug shown upon sheet 1 of the drawings to a brake shoe, the reinforcing back plate B is provided with a plurality of slots 20, 21, 22 and 23, the slots 20 and 21 being adapted to admit respectively the flanges f and g at the bottoms of the end walls of the lug, while the slots 22 and 23 admit respectively 105 the flanges d and h of the lug. When the flanges have been inserted through the sev-

eral slots in the back plate B, these flanges will all be bent inwardly and towards each other, as shown more particularly in Fig. 1 of the drawings, and when so bent, will securely interlock the end lug to the back plate of the shoe. It will be understood that when the cast metal comprising the body A of the shoe is united to the reinforcing back in the casting operation, the flowing of the cast metal about the flanges that attach the end lug to the back plate will effectively aid in holding these flanges in interlocked relation with the back plate.

In the modification of my invention illustrated upon sheet 2 of the drawings, the end lug is made from a sheet metal blank, preferably of the shape shown in Fig. 10. To form the finished end lug from such a blank, the blank is bent upon the lines 10^a and 11^a to form the top C and front or outer and rear or inner walls D and E; it is also bent upon the lines 12^a and 13^a to form the end walls F and G; is bent upon the line 14^a to form the inwardly extending part H, and is bent upon the lines 15^a and 16^a to form the upstanding centering walls I and J. Slits 17 and 18 are formed in the blank to permit the walls I and J to be bent upwardly.

To form the flanges for attaching the lug to the back of the shoe, the blank is bent upon the line 19 to form the long flange d', upon the lines 19^a to form the flanges e, upon the lines 19^b and 19^c to form the flanges f' and g', and in this form of the invention, the part H is formed with a flange or extension h' adapted to interlock with the back plate of the shoe, as will presently appear. The blank is slotted between the flanges e and walls I and J.

The end lug last described is especially adapted to be used in connection with a back plate B' adjacent the end of which is formed a transverse opening 25 (preferably a T-shaped opening) adapted to receive the body of the lug and the upstanding centering walls I and J.

Before the cast metal body A is poured into the pan-shaped back or shell of the shoe, the end lug will be placed within the transverse opening 25 of the back plate B', as shown in Fig. 7 of the drawings, and when in such position, the flanges d', e, f', g' and the extension h' will serve to securely hold the end lug in position. The cast metal forming the body of the shoe will flow about the several attaching flanges and insure the interlocking of these flanges with the reinforcing back plate of the shoe.

By reference more particularly to Fig. 9 of the drawings, it will be seen that when the cast metal is poured within the pan-shaped reinforcing back or shell of the shoe, such metal will flow into the box-shaped body of the lug, forming a cast metal part

a that will serve to reinforce the body of the end lug.

While I have described what I regard as the preferred embodiments of my invention, it will be understood that the details above described may be varied without departure from the scope of the invention and that features of the invention may be employed without its adoption as an entirety.

Having thus described my invention, what I claim as new and desire to secure by Letters Patent is:—

1. The combination with a brake shoe, of an end attaching lug comprising a channel or box-like body extending transversely of the shoe and provided with integral flanges for attaching the lug to the shoe. 80
2. The combination with a brake shoe, of an end attaching lug formed from ductile metal and comprising a channel or box-like body having front, rear and end walls and provided with flanges for attaching the lug to the shoe. 85
3. The combination with a brake shoe, of an end attaching lug comprising an inverted channel or box-like body extending transversely of the shoe, said body having side and end walls provided at their edges with flanges for attaching the lug to the shoe. 90
4. The combination with a brake shoe, of an end attaching lug comprising a channel or box-like body extending transversely of the shoe and having upstanding, inwardly projecting centering walls, and flanges for attaching the lug to the shoe. 95
5. The combination with a brake shoe, of an end attaching lug comprising an inverted channel or box-like body extending transversely of the shoe and having upstanding, inwardly projecting centering walls and having flanges integral with said body for attaching the lug to the shoe. 100
6. The combination with a brake shoe, of an end attaching lug comprising a channel or box-like body extending transversely of the shoe, the inner wall of said body having integral therewith an inwardly extending part provided at its edges with upstanding centering walls. 110
7. The combination with a brake shoe, of an end attaching lug comprising an inverted channel or box-like body extending transversely of the shoe, the inner wall of said body having integral therewith an inwardly extending part provided at its edges with upstanding centering walls, said body and said inwardly extending part being provided with flanges for attaching the lug to the shoe. 115
8. The combination with a brake shoe, of an end attaching lug formed of ductile metal and comprising an inverted channel or box-like body having front, rear and end walls, the front and end walls being formed with attaching flanges, and having formed 120
- 130

- integral with its rear wall an inwardly extending part provided at its side edges with upstanding centering walls and provided at its end with an attaching flange.
- 6 9. The combination with a brake shoe having a reinforcing back, of an end lug having a transversely extending channel or box-like body provided with flanges bent to engage the inner side of said back plate.
- 10 10. The combination with a brake shoe having a reinforcing back provided adjacent its end with a transverse opening, of an end lug having a transversely extending body arranged within said opening, said body having flanges for holding the end lug in place.
11. The combination with a brake shoe having a reinforcing back provided adjacent its end with an opening, of an end lug comprising a transversely extending inverted channel or box-like body located at said opening and having flanges for holding the end lug in place.
- 20 12. The combination with a brake shoe having a cast metal body and a reinforcing back provided adjacent its end with an opening, of an end lug attached to the back at said opening, the cast metal of the brake shoe body extending into said lug.
13. The combination with a brake shoe ³⁰ having a cast metal body and a reinforcing back provided adjacent its end with an opening, of an end lug comprising a transversely extending, inverted channel or box-like body attached to the back at said opening, the cast metal of the brake shoe extending into said lug.
14. The combination with a brake shoe having a cast metal body and a reinforcing back provided adjacent its end with a trans- ⁴⁰ verse T-shaped opening, of an end lug comprising a transversely extending, inverted box-shaped body located within said opening, said lug having an inwardly extending part provided with upstanding centering ⁴⁵ walls and having flanges for holding the end lug in place, the cast metal of the shoe body extending into said lug.
15. The combination with a brake shoe having a reinforcing back provided adjacent its end with a transverse opening, of an end lug comprising an inverted channel or box-like body having flanges to engage the back of the shoe and having an inwardly extending part provided with upstanding ⁵⁰ centering walls and with a flange to engage the back of the shoe.

CLIFTON D. PETTIS.
